UNITED STATES PATENT OFFICE.

JACOB RUSSELL, OF NEWARK, N. J., AND CHARLES BALL, OF GREEN POINT, N. Y., ASSIGNEES, BY DIRECT AND MESNE ASSIGNMENTS, TO THE KEYSTONE HORSE SHOE COMPANY, OF PHILADELPHIA, PA.

HORSESHOE-MACHINE.

SPECIFICATION forming part of Letters Patent No. 268,731, dated December 5, 1882.

Application filed December 29, 1881. (No model.) Patented in England June 23, 1882, No. 2,980.

To all whom it may concern:

Be it known that we, JACOB RUSSELL and CHARLES BALL, both citizens of the United States, the former residing in Newark, Essex county, New Jersey, and the latter residing in Green Point, Kings county, New York, have jointly invented certain Improvements in Horseshoe-Machines, of which the following is a specification.

10 This invention relates to a machine for straightening, shaping, and truing horseshoes after they have been bent, and the clips, calks, and channels formed on and in them.

15 Horseshoes after having been bent on existing machines are usually untrue as to their curves, are warped or "in wind," and have burrs formed on their edges. They also require to have a chamfer, bevel, or concave formed on their upper sides. It is to effect 20 these finishing operations that we have devised the machine which we will now describe.

In the drawings which serve to illustrate our invention, Figure 1 is a front elevation, and Fig. 2 is a side elevation, of the machine, 25 as a whole. Fig. 3 is a plan of the bed of the machine, the frame being in horizontal section on line 3 3 in Fig. 4. Fig. 4 is a vertical longitudinal mid-section taken on line 4 4 in Fig. 3. Fig. 5 is a detached detail view of the upper or die roll and the bed. Fig. 6 is a detached view of the connecting-rod strap. Fig. 7 is a view of the face of the upper die. Fig. 8 is a detached cross-section of one of the levers for operating the lateral dies, taken on line 8 8 in 35 Fig. 4. Figs. 1 and 2 are drawn to a smaller scale than the remaining figures.

Let A represent a substantial bed-piece, and B substantial frames, in which the rolls are mounted.

40 C is a bearing-roll rotatively mounted in the frames B, and D is a traveling bed, which rests on the roll C and bears a die or die-plate, E.

F is an upper roll, mounted in bearing-blocks which slide in the frames B, and are made adjustable vertically by means of screws a a. The roll F is mounted directly over the bearing-roll by preference, and bears the upper rolling die, G.

On one projecting end of the journal of the

roll F is fixed a large toothed wheel, H, which 50 meshes with a pinion, I, on a driving-shaft, J, on which are mounted the usual light and loose pulleys, K.

The bed D has a prolongation, D', which is bolted or otherwise firmly fixed to a cross-head, L, which is mounted to play in cross-head guides M, which extend back of the frames B. These guides are bolted to a fixed bed, N, which is of an I shape, one end being supported on legs O and the other on brackets 60 on the frame B.

On the ends of the cross-head L are wrists b b, which are coupled one to a wrist, b', on a crank, P, on the roll F, and the other to a wrist, b', on the spur-wheel H by means of connecting-rods Q. Rotation of the roll F thus imparts a reciprocating motion to the bed D.

The die E has an elevated central part, c, corresponding in shape to the inside of a horse-shoe, and raised above the general level of 70 the die a distance equal to the thickness of a shoe. When placed in the die the shoe encircles this elevated part c, the toe-calk dropping into a mortise, d, in the die, and the heel-calks dropping into recesses d'. The body of 75 the shoe rests upon the face of the die, the heel-calks rest upon the bottom of their recesses, and the toe-calk rests upon a lifter, e, (see Fig. 4,) with a pyramidal head which fits into the mortise d.

The upper die, G, is shaped like a horseshoe, but is a little larger than the shoe, and its center f is or may be recessed to prevent its contact with the raised center of the lower die. The rim or face f' is given the proper shape 85 or contour to impart to the upper side of the shoe the concave or bevel desired and usually found in horseshoes.

We have described the upper and lower dies, and will now describe the dies which have a 90 lateral movement and serve to preserve the proper curvature of the shoe while it passes between the upper and lower dies. This is accomplished by means of two dies, R R, Figs. 3 and 8, mounted on levers S S, pivoted to the 95 cross-head L at g g, and extending forward over the bed D. As the dies R and levers S are precisely alike, are operated by like means

and simultaneously, it will only be necessary to describe one. The inner or operative edge, h , of the die R is as thick as the horseshoe, and is shaped to fit the outer curved edge of the same. The rear edge, h' , takes under the lever S, and is secured thereto.

In order to adjust the die laterally to or from the shoe, a pair of wedges, i , is arranged between the inner edge of the lever S and shoulders h^2 on the die, as clearly shown in Figs. 3 and 8; and in order to adjust the die lengthwise of the lever a set-screw, j , which screws through a lug, h^3 , on the die, is caused to bear against a shoulder on the lever formed by recessing the latter. These means of setting and fixing the dies in their proper position with respect to the lever and shoe are not absolutely necessary, as the dies R might be fixed permanently to the levers S; but we prefer to secure them adjustably, as shown.

In the upper side of the lever is formed a cam-groove, $k k' k^2$, which is curved at its ends and straight at its middle part. The groove is engaged by a roller, l , mounted rotatively on a bracket, l' , fixed to the frame of the machine. When the bed D (bearing the levers) is approaching the forward end of its stroke the roller l acts upon the curved part k' and throws the levers outward, so that a shoe may be properly placed on the die. On the return-stroke the roller passes into the straight middle part of the groove and throws the levers inward, pressing the die R up to and against the shoe. This pressure continues until the bed approaches the backward or rear end of its stroke, when the roller engages the curved part k^2 of the groove and again throws the lever out, thus releasing the shoe. At this moment the lifter e is pressed upward, and taking under the toe-calk of the shoe raises it out of the recess d in the die E. This is accomplished by means of a cam-lever, m , which is hinged in a groove or slot in the under side of the bed D. This lever takes under the end of the lifter e , and when the bed moves back a swell on the under side of said lever wipes over a cam, m' , fixed on the machine-frame, and the lifter and lever are thrown up. At the moment after the shoe is thus lifted it is brought into contact by the backward movement of the bed with a rod, n , mounted on the fixed bed N, and is thrown or knocked off the die E. This rod n is by preference mounted to slide in its bearings, and a spiral spring, n' , is arranged on it between the bearings in a manner to allow the rod to yield elastically if its end be pressed forcibly back. This is in order that the shoe, before it is entirely released, may be brought against the end of said rod, so as to press it back a short distance, and when the shoe is fully released the elastic force of the spring will be sufficient to drive the shoe off with considerable force.

The front ends of the levers S bear rollers o , and these rollers rest upon bearing-springs p , attached to the bed D, and roll on said springs

when the levers swing out and in their clamping and releasing movements. The purpose of this construction is to raise the dies R a little bit above the bed D, normally, and maintain them in this position; but when they have grasped the shoe, and the die G is brought down upon them and the shoe they will be forced down to the bed D, the springs p yielding to permit this movement.

The lateral movement of the dies R is not intended to effect, ordinarily, any change in the form of the shoe. The shoe will usually be presented to the machine in the proper shape so far as its lateral curvature is concerned. Should it be improperly curved, these dies may correct the defect. Their normal function, however, is primarily to hold the shoe in position while the roller-die is acting on it, and, secondarily, to prevent the formation of a burr on its edge by the vertical movement of said dies, as last described. The outer periphery of the shoe, as is well known, does not present a vertical face when placed flatwise, calks down, as on the die E, the upper edge 90 projecting over the lower edge.

In the ordinary mode of making horseshoes a sharp ragged burr is formed on the upper exterior angle, which must be removed before the shoe is used, and to grind this off is a costly 95 operation. The dies R, by reason of their position partly above the edge of the shoe and their vertical movement as the shoe passes under the rolling die, prevents the formation of this burr entirely.

It is found desirable that when the die G shall have first come into contact with the shoe, as shown in Figs. 4 and 5, the bed D, bearing the shoe, should move a little faster than the periphery of the die G, in order that the metal of the shoe may be slightly "drawn" by said die. Therefore we provide the roll F with a long tooth or projection, q , (seen best in Fig. 5, which engages at the proper moment a shoulder, q' , on the bed D, and accelerates the movement of the latter while the die G is in contact with the shoe. As the bed moves on horizontally the tooth q passes off from the shoulder and does not again come in contact therewith until the next revolution. It is evident that this accelerated movement of the bed would be impossible without some play were allowed in the connection of the connecting rods Q with the moving parts. This we provide for by making the box of the rod to play in the strap, as clearly shown at r in Fig. 6. This play or movement will be about three-fourths of an inch in a working machine.

The vertical movement of the lateral dies R may be nearly or quite equal to the thickness 125 of the shoe—say three-eighths of an inch—and we consider this movement as very important in the working of the machine. In some cases the play of these dies vertically might be entirely independent of the levers S.

The spring p might be replaced by other elastic means for raising the said dies R.

Having thus described our invention, we wish it understood that we do not limit ourselves to the precise construction and arrangement of mechanism herein shown, as it may be varied to some extent without materially departing from our invention; but

What we do claim is—

1. The combination, in a horseshoe-machine, of a reciprocating die arranged to receive the shoe, a rolling die arranged to compress the shoe on the reciprocating die as it is borne along, and lateral dies having a vertical as well as horizontal movement, and made to fit and shape the outer contour of the shoe, said lateral dies being mounted on the bed bearing the reciprocating die, all arranged to operate substantially as set forth.
2. The combination, in a horseshoe-machine, of a reciprocating die to receive and support the shoe, provided with recesses to receive the heel and toe calks, a rolling die arranged to compress the shoe on the reciprocating die as it is borne along, two lateral dies having a vertical as well as horizontal movement and constructed to fit and arranged to compress the shoe as it is borne along, said lateral dies being mounted on the reciprocating bed bearing the lower die, a lifting mechanism, substantially as shown, for lifting the calks of the shoe out of their recesses to free the shoe, and a pushing mechanism for pushing the shoe off the die after it is lifted, all arranged to operate substantially as set forth.
3. The combination, in a horseshoe-machine, of a reciprocating die bearing the shoe, a rolling die to compress the shoe on said reciprocating die as it is borne along, and the mechanism for imparting to the reciprocating die a

slightly greater speed than that of the periphery of the rolling die, which mechanism comprises a long tooth or projection on the rolling die arranged to engage a shoulder on the reciprocating bed at the proper time, substantially as set forth.

4. The combination, with the reciprocating die, recessed to receive the calks of the shoe, the bed D, the roll C, the lifter e, arranged in the toe-calk recess, the lever m, hinged at its front end to the front end of the bed D, and the fixed cam m', arranged in the path of the lever m, substantially as set forth.

5. The combination, with the reciprocating die and its bed, of the lifter e, lever m, cam m', rod n, and its spring n', all arranged to operate substantially as set forth.

6. The combination of the upper roll provided with a long tooth or teeth, q, the reciprocating bed provided with a shoulder, q', the cranks on the upper roll, and the connecting-rods Q, arranged to play endwise for a limited distance on their wrists or wrist-pins, substantially as and for the purposes set forth.

7. The combination, in a machine for truing horseshoes, of the rolling die, the reciprocating die and its bed, the levers S, provided with means, as shown, for imparting to them a limited lateral movement, the dies R, and springs p, all arranged substantially as set forth.

In witness whereof we have hereunto signed our names in the presence of two subscribing witnesses.

JACOB RUSSELL.
